UNITED STATES PATENT OFFICE.

WALTER SHEPPARD, OF CHICAGO, ILLINOIS.

AIRSHIP.

Application filed June 29, 1925. Serial No. 40,305.

My invention relates to improvements in airships, and it consists in the combinations, constructions, and arrangements herein described and claimed.

5 An object of my invention is to provide an airship of the lighter-than-air type of the character described in which particularly novel means is provided for maintaining the airship in a set course during flight 10 and for generally stabilizing the ship during its travel in the air.

A further object of my invention is to provide an airship of the type described in which novel means is employed for steering 15 the course of a ship in the air and in which the mechanism for doing so is entirely disposed within the body of the ship.

20 A further object of my invention is to provide an airship of the lighter-than-air type in which I employ novel means for propelling the ship through the air.

25 A further object of my invention is to provide an airship of the type described which is capable of withstanding severe high winds without damage thereto, and which is thoroughly efficient in operation.

30 Other objects and advantages will appear in the following specification and the novel features of the invention will be particularly pointed out in the appended claim.

My invention is illustrated in the accompanying drawings forming part of this application, in which

35 Figure 1 is a side elevation of an embodiment of my invention, portions thereof being broken away,

Figure 2 is a front elevation of my improved airship,

40 Figure 3 is a sectional view of the airship as illustrated in Figure 1,

Figure 4 is an enlarged view of a part of the airship as shown in Figure 3, and

Figure 5 is a sectional view along the line 5—5 of Figure 4.

45 In carrying out my invention I make use of a gas-tight body member 1. The body member 1 has a gradually tapered prow portion 2 and a gradually tapered stern portion 3, the prow and the stern being of substantially the same contour.

50 Means for rendering the body member 1 substantially rigid is provided in a multiplicity of tie rods 4 which are distributed throughout the entire internal portion of the airship. The body member 1 is cov-

ered with thin metal sheeting, and sealed tight at the seams so that lighter-than-air gas, such as helium, may be disposed within the body in direct contact with the outer sheeting 5.

60 The sheeting 5 is secured to metal I-beams 6 which are in turn secured to the tie rods 4 (see Figure 4).

A metal gas-tight tube or tunnel 7 is projected through the entire body member 1 65 from prow to stern, and its outer edges are formed contiguous with and secured to the sheeting 5 (see Figure 4). This tunnel 7 is square in cross section, as shown in Figure 2 and is substantially as wide as one 70 half of the radius of a section through the body member.

An engine 8 is mounted with its crank shaft on the longitudinal axis of the air ship and of the tunnel 7 which has its axis 75 in common with the axis of the body member, by means of suspension rods 9, and a puller type of propeller 10 is mounted upon the front of the crank shaft adjacent to the forward mouth of the tunnel 7. An engine 11, similar to the engine 8, is mounted at the stern portion of the tunnel 7 by means of suspension rods 12 and has a pusher type of propellor mounted at the rearward end of the crank shaft adjacent to the stern 80 mouth of the tunnel. Two other engines 14, identical to the engines 8 and 9, are mounted at equally spaced distances from one another intermediate the length of the tunnel 7, and each has a pusher type of 85 propeller 16 at the rearward end of its crank shaft.

90 Means for further propelling the ship through the air is provided in seven engines similar to the engines 8 and 9 which are 95 disposed within man housing 18, secured to the body member 1 at substantially equal distances from one another about the circumferential portion of the body member amidships. The engines within the man 100 housings 18 adjacent to the keel of the body member are disposed at greater distances from one another than the remaining engines. Each of these engines has a pusher type of propeller 19 at the rearward portion 105 of its crank shaft for assisting in the propulsion of the ship through the air.

110 With reference to Figure 1 it will be noted that other engines having pusher types of propellers 20 are disposed within

gondolas 21 suspended from the body member 1 at points adjacent to the keel portion of the body member on either side of the forward and stern portions of the body member. There is also an engine at the stern portion of the keel having a pusher type of propeller 22.

All of the man housings 18 and the gondolas 21 have passageways 23 connecting therewith and with an interior common passageway 24 in the interior of the body member 1 by means of which mechanics and operators may ascend from the keel or cargo portion 25 of the airship to the various man housings 18 and may descend to the gondolas 21. In descending to the gondolas from the keel it is necessary to go through longitudinal passages (not shown) communicating with the passage 24 to the passage 23 associated with the gondolas. This longitudinal passage structure in lighter-than-air ships is well known in the art and needs no further illustration.

One of the most important arrangements of passages employed in my ship is the vertical staircase 26, entirely housed to exclude gases, which extends from the keel portion 25 to the tunnel 7, by means of which passengers may ascend to the tunnel 7 of the ship should the airship become disabled and fall upon a body of water.

I shall not describe in detail the arrangement of the cabins within the keel portion 25, since this again is a matter which is entirely within the discretion of the architect who designs the ship, and depends primarily upon the purpose for which the ship is intended. It is enough to say, however, that all of the heavy cargo should be disposed in the keel portion 25 to further maintain the ship in an upright position. Referring now to Figures 4 and 5 it will be noted that I have provided a particularly novel means for steering the course through the air. In the ordinary type of lighter-than-air ship the means for steering the course of the ship is disposed exteriorly of the ship at the stern portion and projects beyond the outer shell. In my improved construction I make use of both elevator and lateral plane or rudder. The elevator consists in a substantially horizontal member 27 which extends from one side of the tunnel to the opposite side and is hingedly mounted at the mid-point of the tunnel by means of a horizontally disposed rod 28. Means for actuating the elevator 27 so as to raise or lower the elevator to effect an upward or downward movement of the prow of the ship is provided in wires or cables 29 and 30 which are secured at their outermost ends to the outer portion of the elevator 27 at 31. The opposite ends of these cables 29 and 30 extend over shives 32 and down through a tube the upper end of which is shown at 33 to the foremost por-

tion of the keel 25, where the pilot cabin is located.

Referring now to Figure 5 which is a sectional view through the mechanism illustrated in Figure 4 taken in a horizontal plane, it will be noted that I have provided a lateral plane or rudder 34 which is disposed between the engine 8 and the rod 28 upon which the elevator 27 is mounted. This rudder 34 extends from the top of the tunnel 7 to the bottom of the tunnel and is hingedly mounted upon a vertical rod 35 forming its axis, which is secured at its top and bottom to the adjacent walls of the tunnel.

Means for actuating the rudder 34 to the left and to the right is provided in lead wires or cables 36 and 37 which are secured at their outermost ends at 38 to the outer end of the rudder 34 and which have their opposite ends extending over shives 39 and extending down through tubes, the upper ends of which are shown at 40, to the forward portion of the keel 26, where the pilot cabin is disposed.

From the foregoing description of the various parts of the device the operation thereof may be readily understood. Let us assume that the ship described is in the air and in the course of flight. During normal flight all of the engines and propellers described are in operation. It will be noted that all but the propeller 10 are propellers of the pusher type, while the propeller 10, because of its peculiar disposition at the mouth of the tunnel 7, is of the puller or tractor type.

As the ship moves through the air a great portion of the air encountered by the prow of the ship will be directed through the tunnel 7, where it will be forced through the tunnel with increased rapidity, due to the presence of the propellers 16, 13 and 10, associated with the tunnel so that the same air will be projected from the tunnel at the stern of the ship with sufficient velocity to urge the ship in a forward direction. This force is greatly augmented by the presence of the propellers 19 and the propellers 20 and 22.

Let us assume that the pilot desires to cause the ship to ascend to a higher altitude. This is done by actuating the mechanism within the pilot house to draw the cable 30 downwardly so as to lower the outer end of the elevator 27. Air passing through the forward portion of the tunnel will strike the elevator so as to cause the forward portion of the ship to be lifted slowly thereby causing the ship to nose upwardly and rise to a higher altitude. When the proper altitude has been reached the elevator is returned to its normal position so that the ship may rest on an even keel. In a similar manner if it is desired to cause the ship to descend, the

cable 29 is drawn so as to lift the outer end of the elevator 27, and thus cause the prow of the ship to nose downwardly.

Lateral movement of the airship in flight is caused by actuation of the rudder 34, which is operated by drawing the cables 36 or 37 by such well known mechanism as is employed in actuating a marine rudder, which in its usual form is a pilot wheel having a drum, about which the opposite ends of the cables are wound in opposite directions, and it is disposed in the pilot cabin. In the event that the engines within the man housings 18 or the gondolas 21 should require attention during flight an operator or mechanic may have ready access thereto by ascending the passage 24 and moving through the passage 23 to the particular man housing or gondola to which it is desired to reach. In descending to the gondolas, it is necessary, as stated before, to move through a horizontal passage which communicates with the passage 24.

Let us assume that for some unforeseen reason the ship has become disabled in flight and that it must alight upon a body of water. Inasmuch as the keel 25 is disposed at the lower part of the ship, and would fall beneath the level of the body of water, some protection must be afforded to the passen-

gers as well as a ready means of escape. This is found in the provision of a staircase 26 by means of which the passengers and crew may ascend to the tunnel 7 and may stay within the tunnel until help arrives or may walk therethrough to the prow or stern portion of the ship and wait until floating objects, life preservers, or the like are brought to them from the cabins or from external sources. 40

I claim:

A lighter than air airship comprising a gas-containing body having a passage of uniform diameter throughout extending therethrough from the prow to the stern of the body, means for propelling the airship disposed in said passage, a rudder pivotally mounted at its forward edge and being disposed entirely within the passage and adjacent to the prow of the airship, and an elevator pivotally mounted at its forward edge and being disposed entirely within the passage and directly in back of the rudder, whereby a movement of said rudder or elevator will cause the air passing through the passage to act upon the prow of the airship for causing the airship to change its course in flight, either up and down, or from side to side. 45 50 55

WALTER SHEPPARD.
